(57) **CLAIM**

The ornamental design for a portable information terminal, as shown and described.

DESCRIPTION

FIG. 1 is a perspective view of a portable information terminal, showing my new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another perspective view thereof as shown in a user environment; and,

FIG. 9 is another perspective view thereof as shown in another user environment.

The broken lines in the figures represent portions of the article which form no part of the claim. The broken lines showing of the strap and clip in FIGS. 8 and 9 are included for the purpose of illustrating environmental structure and form no part of the claimed design.

1 Claim, 9 Drawing Sheets
